SET OF ORNAMENTAL INITIALS FOR JEWELRY

Alfred Dana, Boston, Mass.

Application August 5, 1955, Serial No. 37,339

Term of patent 14 years

(Cl. D64—12)

FIG. 1. FIG. 2.

Fig. 1 is a front view of one of the set of ornamental initials for jewelry showing my new design;

Fig. 2 is a side view thereof; and

Fig. 3 is a front view, on a reduced scale, of the other 25 letters of the alphabet comprising the set of ornamental initials for jewelry; all having substantially the same thickness as shown in Fig. 2.

What is claimed is:

The ornamental design for a set of ornamental initials for jewelry, substantially as shown and described.
